J. L. CUBA,

PUNCH,

APPLICATION FILED SEPT. 4, 1912.

1,083,194.

Patented Dec. 30, 1913.

UNITED STATES PATENT OFFICE.

JOHN L. CUBA, OF TAYLOR, TEXAS.

PUNCH.

1,083,194.

Specification of Letters Patent. Patented Dec. 30, 1913.

Application filed September 4, 1912. Serial No. 718,513.

To all whom it may concern:

Be it known that I, JOHN L. CUBA, a citizen of the United States, residing at Taylor, in the county of Williamson and State of

5 Texas, have invented new and useful Improvements in Punches, of which the following is a specification.

This invention relates to metal punches and has for an object to provide a punch of 10 this character which will be effective in operation, simple in construction, inexpensive in manufacture, and which will possess the maximum punching efficiency with a minimum application of pressure.

15 A further object is the provision of a removable anvil block which may be replaced when injured or worn out, and whose construction renders the same very effective in operation.

20 The invention consists of the features of construction, combination and arrangement of parts, hereinafter fully described and claimed, reference being had to the accompanying drawings, in which:

25 Figure 1 is a perspective view of the punch. Fig. 2 is a fragmentary longitudinal sectional view of the same showing the punch in operation. Fig. 3 is a similar sectional view showing the punch after the 30 operation has been completed.

The punch comprises companion pivoted members 1 and 2, the former comprising a handle portion 3 and a curved jaw 4, and the latter consisting of a handle portion 5 co- 5 extensive with the handle portion 3 of the other member and a straight jaw 6 opposed to the coacting jaw 4. A curved spring 7 is interposed between the handles 3 and 5 to normally maintain the same in separated 40 position to hold the jaws likewise in separated position.

The jaw 4 has its downwardly curved extremity tapered gradually, as at 8, and its end beveled, as at 9, to provide a punch 10, 45 which is adapted to be received by a cylindrical opening 11 in the coacting jaw 6. A longitudinal recess 12 is provided in the upper jaw 6 in communication with the opening 11. A removable anvil block 13 50 formed of hard steel is secured within the said recess by means of a transverse rivet 14 passing through aligned openings in the said jaw 6 and the block 13, or a threaded member may be substituted for the rivet if so 55 desired. The anvil block 13 has its outer end projecting over the opening 11 and is

beveled downwardly, as at 16, a straight cutting edge 17 being thus provided for engagement with the inner face of the punch 10.

60 In operating the punch, the sheet of metal or other object to be punched, is inserted between the jaws of the punch and the handles are gripped so as to force the punch 10 into the opening 11. Upon slight application of pressure, the sharp toe 18 of the punch makes an incision in the metal, and a semi-circular flap is down-struck, due to the fact that the heel 19 of the punch is obtuse and thus does not cut the metal. Upon the 70 application of more pressure, the heel 19 of the punch will coat with the cutting edge 17 of the anvil to sever the above-described flap as it passes below the cutting edge 17 of the anvil 13, thus completing the operation 75 of punching the metal or other material.

The anvil 13 may be removed whenever its cutting edge becomes damaged or worn, and a new one substituted therefor, and in 80 order to renew the sharp point of the punch, it is merely necessary to grind the same into proper shape. It will thus be seen that I have provided a tool of this character which is adapted to last indefinitely and to efficiently serve its purpose whenever used.

A punch constructed in accordance with the invention may be used efficiently for punching holes in tin or other metal, and is especially adapted for use in punching holes 90 in strips of tin or like articles for the reception of attaching nails or tacks. The punch may be operated with very little exertion, as the only point of frictional engagement between the punch and the anvil is at the central portion of its straight cutting edge, and the punch further does not engage any portion of the jaw 6, the opening 11 being large enough to permit the free passage of the punch.

100 What is claimed is:

1. A punching tool comprising companion pivoted members having handles formed on adjacent ends thereof, coacting jaws formed on the opposite ends thereof, one of said jaws being provided with an opening, a removable anvil provided adjacent said opening and having an upwardly and forwardly inclined end face presenting an active cutting edge forming the inner edge of the opening, and a punch formed on the jaw of the other member, said punch being smaller in

diameter than the said opening and adapted to work freely therein, the active end of the said punch being beveled to provide an acute toe and an obtuse heel, the latter being engageable with the cutting edge of the anvil as it passes the same.

2. A punching tool comprising companion pivoted members having handles formed on adjacent ends thereof, a straight jaw formed 10 on the opposite end of one of said members and being provided with an opening, a curved jaw formed on the corresponding end of the other member and having its free end beveled to provide a punch having an

outwardly disposed toe and an inwardly disposed heel, the inner face of the punch jaw being curved concentric with the pivot of the said members, and an anvil mounted within the opening of the other jaw at the inner edge thereof and being engageable 20 with the curved inner face of the punch jaw.

In testimony whereof I affix my signature in presence of two witnesses.

JOHN L. CUBA.

Witnesses:

JEFF WOMACK,
FRANCIS H. WELCH.
